UNITED STATES PATENT OFFICE.

JAY WARREN CLARK, OF NEW YORK, N. Y.

ELECTRIC SIGNAL DEVICE.

Application filed April 27, 1920. Serial No. 376,941.

To all whom it may concern:

Be it known that I, JAY WARREN CLARK, a citizen of the United States, and residing at New York, in the county of Bronx and 5 State of New York, have invented certain new and useful Improvements in Electric Signal Devices, of which the following is a specification such as will enable those skilled in the art to which it appertains to make and 10 use the same.

This invention relates to electric signal devices and particularly to devices of this class which are adapted to operate electric bells, buzzers, annunciators, lamps, switches 15 and various other instruments or electrical appliances, and the object of the invention is to provide a device of the class described which involves an electro-magnet or magnets and an armature actuated by said magnet 20 or magnets, the movement of said armature being governed by the direction of the flow of the current through said magnet or magnets; a further object being to provide means for controlling and regulating the flow of the 25 current through the magnet or magnets; a still further object being to provide adjustable means cooperating with the armature and in the electric circuit to the magnet or magnets for controlling the movement of 30 said armature; and with these and other objects in view the invention consists in a device of the class and for the purpose specified which is simple in construction and operation and efficient in use, and which is 35 constructed and operated as hereinafter described and claimed.

The invention is fully disclosed in the following specification, of which the accompanying drawing forms a part, in which the 40 separate parts of my improvement are designated by suitable reference characters in each of the views, and in which:—

Fig. 1 is a diagrammatic plan view of my improved electrical device and illustrating 45 one use thereof;

Fig. 2 a partial section on the line 2—2 of Fig. 1, with part of the construction omitted; and,

Fig. 3 a partial section on the line 3—3 of 50 Fig. 1 and on an enlarged scale.

In Figs. 1 and 2 of the drawing I have shown at 5 a permanent magnet which comprises, in the form of construction shown, a base portion 6 at the ends of which are upwardly directed ears 7 and 8. Secured to the ear 8 is a yoke-shaped magnet member

9 preferably composed of soft iron. Mounted in the end portions 10 of the yoke-shaped magnet member 9 are electro-magnets 11 and 12, the cores 13 of which project into close 60 proximity at the adjacent faces of said electro-magnets 11 and 12.

Secured to the ear 7 at the other end of the magnet 5 is a U-shaped hinge member 14 in which is pivoted, as shown at 15, an 65 armature arm 16 which extends longitudinally of the base 6 of the magnet 5, and the free end portion 17 of which is located between the projecting ends of the cores 13 of the electro-magnets 11 and 12. The free 70 end of the armature arm 16 carries, in the form of construction shown, a hammer rod 18, the end of which is provided with a knob 19 which is adapted to strike a bell or gong 20 mounted on a suitable support 21, but 75 it will be understood that the armature arm may be mounted in connection with any suitable mechanism which it is designed to operate.

Secured to one side of the armature 80 arm 16 adjacent to the pivoted end thereof are two spring and electrical conducting members 22 and 23 and to the other side of said armature arm is secured another spring member 24. Mounted at one side of 85 the armature arm 16 are two supports 25 and 26 in which are adjustably mounted contact points 27 and 28 respectively which, in the form of construction shown, consist of screws. Mounted at the other side of the 90 armature arm 16 is another support 29 in which is adjustably mounted a screw 30. It will be seen on a consideration of Fig. 1 of the drawing that the contact point 27 is 95 adapted to operate in connection with the spring member 22, while the contact point 28 is adapted to operate in connection with the spring member 23, the screw 30 in connection with the spring member 24.

The above described construction completes the various mechanical parts of the device, and for the purpose of illustrating the use of the invention and the electric circuit to the various parts above set out, I have shown in Fig. 1 of the drawing at 31 100 and 32 two circuit wires which are connected with a source of electrical supply having a direct current and, in practice, I provide two switch devices 33 and 34 which are adapted to open and close both sides of the circuit 105 through the wires 31 and 32 to control the flow of the current into and through the de-

vice. The switch devices 33 and 34 are both of the same general construction and each consist of a top pair of spring contact devices 35 and 36, and a bottom pair of spring contact devices 37 and 38, the separate pair of contact devices being separated from each other by a strip of insulating material 39, as is clearly illustrated in Fig. 3 of the drawings.

10 In practice, the main circuit wire 31 is placed in circuit with the contact 38 of the switch device 33 through a wire 40 and in circuit with the contact 36 of the switch device 34 through a wire 41, while the main circuit wire 32 is placed in circuit with the contact 36 of the switch device 33 through a wire 42, and in circuit with the contact 38 of the switch device 34 through a wire 43. My improved signal device is provided 15 with two binding posts 44 and 45 with which are connected respectively circuit wires 46 and 47. The wire 46 is placed in circuit with the contact 35 of the switch device 33 through a wire 48 and in circuit with the contact 35 of the switch device 34 through a wire 49, while the circuit wire 47 is placed 20 in circuit with the contact 37 of the switch device 33 through a wire 50 and with the contact 37 of the switch device 34 through a 25 wire 51.

The above described wiring places both pair of contacts in each of the switch devices 33 and 34, in the main circuit wires 31 and 32 and the circuit wires 46 and 47, which 30 connects with the binding posts 44 and 45 and, in the construction shown, a circuit wire 52 is connected with the binding post 44 and with the support 26 of the contact point 28, and a circuit wire 53 is connected 35 with the binding post 45 and with the electro-magnet 12. A branch wire 54 is connected with the wire 53 and with the support 25 of the contact point 27. Another circuit wire 55 is connected with the electro-magnet 12 and with the electro-magnet 11 to place the same in a common circuit and another circuit wire 56 is connected with the electro-magnet 11 and with the pivoted end portion of the armature arm 16 as shown at 40 57. The above described construction completes the electric circuit or wiring through the signal device or the various parts thereof, and the use of my improvement will be readily understood from the foregoing description when taken in connection with the accompanying drawing and the following statement.

With my improved electric signal device I provide an armature arm which is capable of movement in opposite directions and is capable of performing any two of the following operations by adjusting the contact points 27, 28 and screw 30, and for the purpose of this description the magnet 11 45 will be regarded as the right hand side of

the device and the magnet 12 as the left hand side thereof. In one adjustment of the device the armature arm may move to the right or move to the left; in another adjustment the armature arm may vibrate to the right or vibrate to the left; in another adjustment the armature arm may relay to the right or vibrate to the left; and in still another adjustment the armature arm will vibrate to the right or relay to the left.

75 In order to fully understand the foregoing the following is submitted. The upwardly directed ear 8 of the permanent magnet will be the "S" pole in such magnet, while the ear 7 will be the "N" pole thereof; it will therefore be apparent that the magnetic yoke 9 will have "S" polarity and the armature becomes a magnetic member having "S" polarity at its pivoted end and "N" polarity at its free end, and the core pieces 13 of the 80 magnets 11 and 12 will become "S" polarity due to their connection with the magnetic member 9.

85 The primary principle upon which the invention is based consists in the changing of the magnetic polarity of the electro-magnets 11 and 12 by controlling the direction of the current passed therethrough on a two wire circuit in such manner that the armature arm is caused to move toward either one of 90 said electro-magnets, and by means of the adjustable contact points 27, 28 and screw 30 I may control the movement of said armature in such manner as to cause the same to vibrate toward or relay to either of said 95 electro-magnets. The device is operated as a buzzer in the vibratory action of the armature arm to the left, and this operation is produced by adjusting the screw 30 so as to increase the tension of the spring member 100 105 24 and to hold the spring member 23 in engagement with the contact point 28 and the contact point 27 is adjusted so as to disengage the same from the spring member 22 as shown in Fig. 1 of the drawing. After 110 the above adjustment has been made the switch device 34 is operated, which operation causes the current to flow into the signal device through the wires 49—46 to the binding post 44 through the wire 52 of the 115 contact point 28 through the spring member 23, armature arm 16 and wire 56 to the electro-magnets 11 and 12 and from the electro-magnet 12 through the wire 53 to the binding post 45 and out through the wire 47.

120 The above operation of passing the current through the signal device will by reason of the direction of the winding on the electro-magnets cause the electro-magnet 11, which has been assumed to be "S" polarity near the 125 armature, to become "N" polarity near said armature, and would also cause the electro-magnet 12 to increase its magnetism with its polarity unchanged thus the armature arm 16 will be repulsed by the magnet 11 and at-

tracted by the magnet 12 or, in other words, would swing to the left. When the armature arm is swung to the left, as above stated, the spring 22 engages the contact point 27 5 which short-circuits the signal device through the wire 54 and the current ceases to flow through the magnets 11 and 12 and the magnetic field returns to its normal state and the armature arm will again assume its 10 original position, and this causes the spring 22 to become separated from the contact point 27 and the short-circuit is thus removed and if the switch device 34 is held in an operative position the current will 15 again flow through the magnets 11 and 12 and the above described operation repeated, and the action of the armature arm, or the hammer rod 18 connected therewith, will produce a buzzing sound.

20 The signal device is operated as a bell in the vibratory action of the armature arm to the right and this result is accomplished by operating the switch device 33 to cause the current to enter the sounding device 25 through the binding post 45 and thus through the wire 53, electro-magnets 12 and 11, wire 56 and armature arm 16 and through the spring 23 and contact point 28 and out through the binding post 44 through 30 the wire 52. A direct current passed through the electro-magnets in the direction above set out will cause the magnet 11, which is assumed to be of "S" polarity near the armature arm, to increase its magnetism with the polarity unchanged, and 35 the magnet 12 will be changed to "N" polarity near the armature arm and the action of said magnets will cause the armature arm to be attracted by the magnet 11 40 and repulsed by the magnet 12 or, in other words, the armature arm 16 will be moved to the right.

In the above described operation the contact points 27 and 28 and screw 30 are in the 45 same adjusted position as in the vibratory action of the armature arm to the left, as hereinbefore described, but when the armature arm is swung to the right the spring member 23 is disengaged from the contact point 28 and the circuit is open or broken thus causing the current to cease to flow 50 through the magnets 12 and 11, and the magnetic field returns to its normal state and the armature is brought back to its 55 original position. If the switch device 33 is held in operation, the electric circuit, above described, will again be closed and the 60 above operation again repeated to vibrate the arm 16 to the right, which operation will cause the head 19 to strike the bell or gong 20.

From the foregoing description of the vibratory action of the armature arm to the left and to the right, it will be apparent 65 that it is necessary to employ means for

reversing the direction of the current to pass through the signal device, and this direction governs the movement of said armature arm.

When it is desired to operate the device 70 for the purpose of moving the armature arm to the left and to the right, the contact point 28 is adjusted so as to constantly bear on or be held in engagement with the spring 23 regardless of the position of the armature arm and the contact point 27 is adjusted so that the spring 22 cannot engage the same in any position of the armature arm 16. With the parts so adjusted it will be apparent that the circuit is always closed through 75 both of the electro-magnets 11 and 12 and the direction of moving the armature arm 16 will be governed by the switch devices 33 and 34, that is to say, if the switch device 33 is operated the armature arm will 80 move to the right, and if the switch device 34 is operated said armature arm will move to the left. The armature arm will remain in engagement with either electro-magnet 85 as long as the switch device is held in an operative position.

In operating the signal device to move the armature arm to the left and vibrating the same to the right, the contact point 27 is adjusted so that the spring member 22 cannot come in engagement with said contact point when the armature arm is moved to the left, and the contact point 28 is adjusted so that it will be in contact with the spring member 23 when the armature arm is in its 90 normal position but so that the spring member 23 will move out of engagement with the contact point 28 when the armature arm is swung to the right. In this adjustment and when the current enters the instrument 100 in the manner hereinbefore set out to attract the armature arm to the left there is no means provided to alter the circuit and the armature arm should remain in such position until the circuit is opened through the 105 switch device 34. When the current enters the instrument in the opposite direction and the armature arm is moved to the right the circuit is opened through the contact point 28 and spring 23 and the armature will 110 return to its original position and the circuit will again be closed, and the above operation repeated to vibrate the armature arm as long as the circuit is closed through the 115 switch device 33.

In operating the signal device to vibrate the armature arm to the left and to move the same to the right, the contact point 28 is adjusted so that it will always be in engagement with the spring 23 and the contact point 27 adjusted into the position shown in Fig. 1 and so that the spring member 22 will engage said contact point when the armature arm is moved to the left. In this 125 adjustment and when the current enters the 130

41
instrument in such direction as to attract the armature arm to the right, said arm will remain in such position as long as the circuit is closed through the switch device 33. 5 When the current enters the instrument in the opposite direction so as to attract the armature arm to the left, the spring 22 is brought into engagement with the contact point 27 and the instrument is short-circuited and the armature arm will return to its normal position and the circuit will again be completed to produce a vibratory movement of said arm to the left as long as the circuit is closed through the switch 10 device 34.

From the foregoing description it will be understood that my improved device may be used for various purposes, as for example, the operation of bells, buzzers and other alarm devices, and may also be used for the purpose of operating annunciators, lamps, switches and various other and similar devices; and while I have shown and described specific forms of switch devices 33 and 34, it will be understood that any means may be provided for opening and closing both sides of the circuit to the electro-magnets 11 and 12, and various other changes in and modifications of the construction herein shown and described may be made, within the scope of the appended claims, without departing from the spirit of my invention or sacrificing its advantages.

Having fully described my invention, 25 what I claim as new and desire to secure by Letters Patent, is:—

1. A signal device of the class described comprising a permanent magnet, a polarized armature arm pivotally mounted in connection with one portion of said magnet and extending longitudinally thereof, electro-magnets connected with the other end portion of said permanent magnet and at the opposite sides of the free end portions of said armature arm and in connection with which said armature arm is adapted to operate, said electro-magnets and armature arm being in a common electric circuit, and adjustable means in juxtaposition to and cooperating with said armature arm for controlling and regulating the movement thereof.

2. A signal device of the class described comprising a permanent magnet, a polarized armature arm pivotally mounted in connection with one end portion of said magnet and extending longitudinally thereof, electro-magnets connected with the other end portion of said permanent magnet and on the opposite sides of the free end portion of said armature arm and in connection with which said armature arm is adapted to operate, said electro-magnets and armature being in a common electric circuit, tensional contact members on said

armature arm and adjustable contact devices in circuit with said electro-magnets adapted to cooperate with said tensional conducting members for controlling and regulating the movement of said armature. 70

3. A signal device of the class described comprising a permanent magnet, a polarized armature arm pivotally mounted in connection with one end portion of said magnet and extending longitudinally thereof, electro-magnets connected with the other end portion of said permanent magnet and on the opposite sides of the free end portion of said armature arm and in connection with which said armature arm is adapted to operate, said electro-magnets and armature being in a common electric circuit, tensional contact members on said armature arm, adjustable contact devices in circuit with said electro-magnets adapted to cooperate with said tensional conducting members for controlling and regulating the movement of said armature, and means for controlling the circuit to said electro-magnets, armature arm and contact devices. 85 90

4. A signal device of the class described comprising a permanent magnet, a polarized armature arm pivotally mounted in connection with one end portion of said magnet and extending longitudinally thereof, electro-magnets connected with the other end portion of said permanent magnet and on the opposite sides of the free end portion of said armature arm and in connection with which said armature arm is adapted to operate, said electro-magnets and armature being in a common electric circuit, tensional contact members on said armature arm, adjustable contact devices in circuit with said electro-magnets adapted to cooperate with said tensional conducting members for controlling and regulating the movement of said armature, and adjustable means cooperating with said armature arm which in combination with said 95 100 105 adjustable contact devices are adapted to control and regulate the movement of said armature arm. 110

5. An electric signal device of the class described comprising two electro-magnets 115 placed in an electric circuit, a polarized armature arm mounted between said magnets and in circuit therewith, and means involving three adjustable devices cooperating with said armature and two of which are in said circuit for regulating the movement of said armature and for governing the character of the movement imparted to said arm.

6. A signal device of the class described 125 comprising two electro-magnets in a common electric circuit, a polarized armature freely disposed between and adapted to cooperate with said magnets, three tensional devices carried by said armature, and three 130

adjustable contact devices in juxtaposition to and adapted to cooperate with the separate tensional devices of said armature and two of which are in said circuit to control and regulate the movement of said armature.

7. An electric signal device of the class described comprising a substantially T-shaped permanent magnet, two electro-magnets mounted in connection with the cross head portion of the permanent magnet and in a common electric circuit, an armature arm pivotally mounted in connection with said permanent magnet and freely disposed between the adjacent ends of the electro-magnets, and means on said armature arm and cooperating therewith and in circuit with said electro-magnets for controlling and regulating the movement imparted to said armature arm.

8. An electric signal device of the class described comprising a substantially T-shaped permanent magnet, two electro-

magnets mounted in connection with the cross head portion of the permanent magnet and in a common electric circuit, an armature arm pivotally mounted in connection with said permanent magnet and freely disposed between the adjacent ends of the electro-magnets, means on said armature arm and cooperating therewith and in circuit with said electro-magnets for controlling and regulating the movement imparted to said armature arm, said means involving a plurality of tensional devices on said armature arm, and adjustable contact devices cooperating with said tensional devices.

In testimony that I claim the foregoing as my invention I have signed my name in presence of the subscribing witnesses this 24th day of April 1920.

JAY WARREN CLARK.
